HOOD LATCH STRUCTURE

George Janonis, Detroit, Mich.

Application March 6, 1950, Serial No. 147,822

7 Claims. (Cl. 292—50)

The present invention relates to hood latch structure and more particularly to structure designed to latch the hood of an automobile in closed position.

It is an object of the present invention to provide a simplified hood latch structure which nevertheless operates efficiently to retain the hood firmly in latched position while preventing rattling of the hood, and at the same time effective to prevent accidental upward movement of the hood if the latching means becomes inoperative during driving of the vehicle.

It is a further object of the present invention to provide hood latch means fully releasable from the interior of the driving compartment of the vehicle, which at the same time has safety means associated therewith to prevent accidental upward swinging of the hood if the hood is accidentally released from fully latched position.

It is a further object of the present invention to provide hood latch mechanism which is adjustable as to forces applied so that it may be adjusted to operate satisfactorily with hoods having different weight and suspension characteristics.

It is a feature of the present invention to provide hood latch mechanism comprising a pair of cooperating latch plates associated with a notched latch bolt.

It is a further feature of the present invention to provide hood latch mechanism comprising a pair of pivoted latch plates having spring means urging said plates toward latching position, means interconnecting said plates for simultaneous swinging movement, a latching bolt adapted to be moved into the space between said plates and having latching notches thereon, a spring balance plate below said latch plates effective to engage the inserted end of said latch bolt, said latch bolt preferably being provided with an enlarged safety head, and means operable from within the driving compartment of the vehicle for effecting movement of said latch plates to bolt releasing position.

Other objects and features of the invention will become apparent as the description proceeds, especially when taken in conjunction with the accompanying drawings, wherein:

Figure 1 is a fragmentary front elevation of the hood latch structure.

Figure 2 is a horizontal section on the line 2—2, Figure 1.

Figure 3 is a transverse section on the line 3—3, Figure 2.

Figure 4 is a sectional view similar to Figure 3 illustrating the parts in a different relative position.

Figure 5 is a view similar to Figures 3 and 4 illustrating the parts in yet another relative position.

Figure 6 is a fragmentary section on the line 6—6, Figure 2.

Figure 7 is a fragmentary section on the line 7—7, Figure 2 showing in addition, remote controlled operating mechanism associated with the hood latch structure.

Referring now to the figures the hood latch structure comprises a plate 10 shaped to fit at the forward upward

end of the motor compartment. The shape of the plate 10 is itself unimportant except that it will be shaped to conform to the particular vehicle in which the hood latch structure is mounted. The plate is designed 5 to be fastened to the top side of the cross bar structure between the front fenders, in rear of the grille. The plate 10 centrally thereof, includes an enlarged opening 12 as best seen in Figure 3. To the upper surface of the plate 10 are secured mounting and actuating rods 14 and 16. The rod 14 includes straight portions 18 and 20 and the rod 16 includes straight portions 22 and 24 by means of which the rods are pivoted to the plate 10 by pivot brackets 26 and 28. Intermediate the straight portions 18 and 20, the bar 14 has an arcuately curved portion 30. Intermediate the straight portions 22 and 24, the bar 16 has an arcuately curved portion 32. At one end the bars 14 and 16 are provided with depending levers 34 which extend through an opening 36 formed in the plate 10. As best seen in Figure 6, the depending lever portions 34 of the bars are provided with openings 38 through which extend a spring supporting pin 37 carrying compression springs 38 which at their outer ends bear against spring seats 40. The arrangement is such that the lever portions 34 are biased by the springs 38 in 15 a direction tending to rock the arcuate portions 30 and 32 of the bars downwardly toward the plate 10.

The bar 16 at its opposite end is provided with an upstanding actuating arm 41 by means of which the bar may be rocked about an axis coincident with its straight portions 22 and 24. Adjacent the actuating arm 41, as best seen in Figures 2 and 7, the straight portion 24 of the rod 16 has a camming projection 42. The adjacent end of the rod 14 is provided with a cooperating cam portion 44, these parts cooperating as best seen in Figure 7 to effect simultaneous rocking movement of the rods.

Rigidly secured to the arcuate portions 30 and 32 of the rods are latch plates 46 and 48. These latch plates, as best seen in Figures 2 through 5, are downwardly dished to provide a downwardly tapered guiding surface for a latch bolt later to be described. The confronting edges 50 and 52 of the latch plates are recessed as indicated at 54 to partially envelop the latch bolt.

The springs 38 previously described, thus exert a force tending to cause the edges 50 and 52 of the latch plates to approach but permit yielding of the latch plates.

Rigidly secured to the forward end of the hood of the vehicle is a latch bolt 60. This latch bolt is preferably fastened to a rigid cross piece of the hood and is movable upwardly and downwardly therewith. The latch bolt 60 is provided with an enlarged head 62 constituting a safety catch and above the head 62 the bolt 60 is provided with one or more additional notches 64 which cooperate with the latch plates to retain the hood in predetermined latched position.

Depending from the plate 10 are a pair of threaded members 66, each of which is shown as bolted to the plate as by the nuts 68. The threaded members 66 includes heads 70 against which the lower ends of compression springs 72 bear. The upper ends of the springs 72 engage against a pressure plate 74 and urge the same upwardly. For this purpose the pressure plate 74 is provided with openings which serve to guide the plate for vertical movement on the threaded members 66. Adjustable stop nuts 76 are provided on the threaded members and determine the upper limit of motion of the pressure plate 74. The effectiveness of the spring 72 may of course be adjusted by screwing the threaded members 66 upwardly to bring the heads 70 closer to the plate 10 and by correspondingly moving the stop nuts 76 downwardly.

Conveniently, the pressure plate 74 may extend diagonally across the opening 12 in the plate 10 and for

this purpose the threaded members 66 may constitute two of the four members required to attach the brackets 26 and 28 to the plate 10.

The operation of the mechanism described above is believed apparent, but will be reviewed for purposes of completeness.

Referring first to Figure 5 the latch bolt 60 is shown in the position which it will assume upon first engagement with the latch plates 46 and 48. In this figure the enlarged head 62 of the latch bolt is shown as having forced the edges 52 and 54 apart a small distance which is insufficient to permit passage of the enlarged head or safety catch therethrough. Upon further downward movement of the latch bolt 60 the latch plates 46 and 48 will continue to rock apart until the enlarged head 62 passes between the edges 52 and 54 of the latch plates. At this time the parts will assume the position illustrated in Figure 3 which shows the enlarged head 62 as engaged beneath the latching edges of the latch plates 46 and 48. At this time the hood is retained against upward movement but is ordinarily not tightly latched down. Further movement downwardly of the latch bolt 60 results in the parts assuming the position illustrated in Figure 4. In this figure the pressure plate 74 has been moved downwardly thus compressing the springs 72 and applying an upward force to the latch bolt 60. However, at this time the latch bolt 60 has assumed a position such that the latch plates 46 and 48 have engaged on one of the several notches located above the latching surface provided by the enlarged head or safety catch 62. The pressure plate 74 will exert an upward force on the latch bolt 60 tending to retain the engaged notch 64 firmly against the edges of the latch plates 46 and 48 and thus will retain the hood against rattling. At the same time, the number of notches 64 provided will be such in number and so designed as to spacing as to insure adequate closure of the hood when retained in latched position.

One of the practical disadvantages of the types of hood latches most commonly employed today is that they require not only manipulation of a release from the driver's compartment, but also manual release of an independent safety catch. According to the present invention the safety catch is provided by the laterally enlarged head 62 on the bolt and this safety catch is releasable by mechanism actuated from the driver's compartment. This mechanism may take any convenient form but is herein illustrated as comprising a wire 80 secured at one end to the actuating arm 41 through a compressible spring 82 and a spring stop 84 secured to the end of the wire 80 as by a set screw indicated at 86. Within the driver's compartment suitable means are provided for pulling on the wire. In Figure 7 this means is shown as a bell type crank lever 88 having a first arm 90 to which the opposite end of the wire is secured, and a second actuating arm 92. The lever 88 is pivoted to a mounting bracket 94 which may conveniently be located on the floor board or on the dash or instrument board. Thus for example, the lever 88 may be positioned so as to be actuated by the foot of the driver.

With the parts in the relationship illustrated in Figure 4, initial movement of the lever 88 will effect sufficient rocking movement of the latch plates 46 and 48 to release the latch bolt 60. At this time compression springs 72 will move the pressure plate 74 upwardly thus moving the hood toward open position. However, the enlarged head 62 which constitutes a safety catch, will engage the inner edges of the latch plates 46 and 48. Further movement of the lever 88 will result in further rocking movement of the latch plates 46 and 48 to a position in which they will permit upward passage of the enlarged head 62.

It is important to note that the pressure plate 74 is provided with a depression 96 centrally thereof in position to be engaged by the rounded underside of the head 62 of the latch bolt 60. Further, as best seen in Figure 3,

the pressure plate 74 is spaced from the stops 76 when the upper surface of the head 62 engages the inner edges of the latch plates. Accordingly, the pressure plate 74 serves as a guide for insuring that the lower end of the latch bolt moves upwardly centrally between the edges 50 and 52 of the latch plates, and particularly in centralized relation between the recesses 54 provided in these edges.

If desired, the lever 88 or other actuating device may 10 be operated in such a manner as to effect full release of the latch plates in a quick motion. In this case the latch plates are moved immediately from a latched position to a fully open position which will permit passage of the safety catch or enlarged head 62 therethrough. When the 15 operation is performed in this manner the compression springs 72 will cause the pressure plate 74 to move upwardly relatively quickly and thus to project the latch bolt and the forward end of the hood upwardly a short distance to facilitate further manual opening.

20 It is contemplated that the types of springs employed at 72 will be selected in accordance with the unbalanced weight of the hood and will be sufficiently strong to retain the hood against rattling. As previously stated, minor 25 adjustments in the effectiveness of the spring may be effected by adjustment of the threaded members 66 and the stop nuts 76.

The latch plates 46 and 48 are dished as previously 30 described so as to provide downwardly converging guiding surfaces which will guide the head 62 of the latch bolt into proper relation with the recessed portions 54 of the plates. It will be noted that the latch plates 46 and 48 are mounted for swinging movement about spaced parallel axes located above and slightly outwardly from the innermost position of the recessed edge portions 50 and 52. 35 Accordingly, as pressure is applied by the bolt 60 to these plates these edge portions move in a direction which is for the most part outwardly but includes a small downward component of motion. Accordingly, the upward pressure applied to the latch bolt 60 by the compression springs 40 72 through the pressure plate 74 serves to retain the pressure plate firmly in latched position.

The drawings and the foregoing specification constitute 45 a description of the improved hood latch structure in such full, clear, concise and exact terms as to enable any person skilled in the art to practice the invention, the scope of which is indicated by the appended claims.

What I claim as my invention is:

1. Hood latch structure comprising a mounting plate having an opening therethrough, for mounting on the front end of an automobile, a pair of concavely dished latch plates having opposed lower notched edges extending below said opening, hinge means for said latch plates located above said mounting plate, said hinge means having axes extending generally parallel to said edges and comprising bars having curved portions secured to the upper edges of said plates, transversely extending lever arms on said bars, spring means connected to said lever arms and urging said latch plates toward latched position, a release lever extending transversely from one of said bars, cam means between said bars providing for simultaneous swinging of said bars by said release lever, said structure adapted to receive the end of a headed latch bolt movable vertically between said latch plates, and having latch surfaces engageable by the edges of said latch plates.

2. A hood latch comprising a pair of hinged latch plates having cooperating edge portions in confronting relation, hinge means for said plates providing for movement of said edges toward and away from each other, resilient means urging said plates into position with said edge portions adjacent, a latch bolt movable downwardly between said plates having latching surfaces engageable with said edges preventing withdrawal of said bolt, release means comprising a lever secured to one of said plates, camming means interconnecting said plates to provide simultaneous

swinging thereof, and resilient means below said latch plates engageable with the lower end of said bolt and urging it upwardly, said resilient means comprising a transverse pressure plate and springs urging said pressure plate upwardly, said pressure plate having an upwardly facing recess to receive the end of said bolt and to guide said bolt upwardly when released by said plates.

3. In a hood latch structure, a pair of latch plates having confronting edges, hinge means for said plates providing for movement of said edges toward and away from each other, resilient means urging said plates toward latched position, a latch bolt movable downwardly between said plates, a pressure plate below said latch plates in position to be engaged by the lower end of said latch bolt, and resilient means urging said pressure plate upwardly to retain said bolt firmly in latched position to prevent rattling of the hood, said pressure plate being formed with an upwardly facing recess to receive the lower end of said latch bolt and to guide said bolt upwardly when released by said plates.

4. Hood latch structure comprising a pair of concavely dished latch plates having opposed lower notched edges, hinge means for said latch plates located above said edges, said hinge means having axes extending generally parallel to said edges and comprising bars having curved portions secured to the upper edges of said plates, transversely extending lever arms on said bars, spring means connected to said lever arms and urging said latch plates toward latched position, said latch plates being adapted to receive therebetween the lower end of a latch bolt movable vertically downwardly into latched engagement between said latch plates, and having latch surfaces on the bolt adapted to be engaged by the edges of said latch plates.

5. A hood latch adapted to cooperate with a latch bolt comprising a pair of latch plates concavely dished in the direction of movement of the latch bolt into engagement therewith, said plates having normally confronting edges provided with registering notches to receive the latch bolt, the concave dished construction of the latch plates being adapted to cause the latch plates to serve as guide means effective to center the latch bolt with respect to the notched edges of the latch plates, hinge means for said latch plates, the axis of said hinge means extending perpendicular to the direction of motion of the latch bolt and being disposed laterally from the edges of the dished plates so that forces applied vertically upwardly on the confronting edges of the latch plates tend to force the latch plates to swing toward each other, resilient means biasing said latch plates in a direction to cause their confronting edges to approach each other, means interconnecting said latch plates effective to provide equal swinging movement thereof, and operating means for swinging said latch plates in a direction to cause separation of said confronting edges.

6. A hood latch bolt adapted to be secured to the hood of an automotive vehicle to extend downwardly there-

from and to cooperate with latch means comprising a pair of bolt engaging latch members movable toward and away from each other, said bolt having a plurality of oppositely disposed pairs of latch engaging surfaces provided 5 along said bolt above the lower end thereof, said bolt having at its lower end a laterally enlarged head adapted to move into position below the latch members to require substantially greater separation between the latch members to release said head than to disengage the latch members from a pair of latch engaging surfaces.

7. A hood latch comprising a mounting plate having an opening therethrough, pivot mounting means comprising hinge pins having aligned end portions and laterally curved intermediate portions disposed adjacent 15 opposite edges of the opening at one side of said plate, dished latch plates having upper edge portions engaged with the laterally curved intermediate portions of said pins, said latch plates extending downwardly through the opening in said mounting plate and converging toward 20 each other, the lower edges of said latch plates constituting latching edges engageable with a headed pin movable downwardly through the opening, an actuating arm on one of said pins, cam means connecting said pins for simultaneous swinging, said pins having bias arms at corresponding ends thereof movable away from each other upon separation of the lower edges of said latch plates, said bias arms having aligned openings, a guide pin in 25 said openings, and compression springs on the end portions of said guide pins opposing separation of said bias arms.
